(57) **CLAIM**

The ornamental design of a professional spray sink mixer, as shown and described.

DESCRIPTION

FIG. 1 is a perspective view of a professional spray sink mixer according to a first embodiment of the present invention;

FIG. 2 is a left side elevational view of the professional spray sink mixer of FIG. 1;

FIG. 3 is a right side elevational view of the professional spray sink mixer of FIG. 1;

FIG. 4 is a rear elevational view of the professional spray sink mixer of FIG. 1;

FIG. 5 is a front elevational view of the professional spray sink mixer of FIG. 1;

FIG. 6 is a bottom plan view of the professional spray sink mixer of FIG. 1; and,

FIG. 7 is a top plan view of the professional spray sink mixer of FIG. 1.

No claim is made to the material illustrated with dashed lines.
